UNITED STATES PATENT OFFICE.

THOMAS F. SOMERS, OF NEW YORK, N. Y.

DESIGN FOR A CORSET.

44,695.

Specification for Design. Patented Sept. 23, 1913.

Application filed July 31, 1913. Serial No. 782,358. Term of patent 14 years.

To all whom it may concern:

Be it known that I, THOMAS F. SOMERS, a citizen of the United States, residing at the city of New York, in the county and State of New York, have invented a new, original, and ornamental Design for Corsets, of which the following is a specification, reference being had to the accompanying drawing, forming part thereof.

The figure is an elevation of an open corset showing my new design.

I claim:

The ornamental design for a corset, as shown.

THOMAS F. SOMERS.

Witnesses:

GEORGE V. GREE, Jr.,
CHARLES G. SEWARD.
